UNITED STATES PATENT OFFICE.

WILLIAM W. GREEN, OF NILES, MICHIGAN.

PLOW.

1,154,307.

Specification of Letters Patent. Patented Sept. 21, 1915.

Application filed June 22, 1914. Serial No. 846,501.

To all whom it may concern:

Be it known that I, WILLIAM W. GREEN, a citizen of the United States, and a resident of Niles, county of Berrien, and State of Michigan, have invented certain new and useful Improvements in Plows, of which the following is declared to be a full, clear, and exact description.

This invention relates to plows, and more particularly to power operated plows, and its principal object is to provide a plow capable of plowing forward and back across the field without the necessity of turning it around at the end of each furrow. With the use of the ordinary plow, much waste space is left at the ends of the field because of the necessity of turning the plow around, whereas with the present invention the plow may be run to the end of the field without losing practically any of the space. To such ends, this invention consists in a power operated plow, having one or more plow shares at each end of the structure, each plow share being adapted to be lowered into working position or raised out of the furrow.

The invention further consists in the several novel features hereinafter fully described and particularly defined in the claims.

The invention is clearly illustrated in the drawings furnished herewith of which:

Figure 1 is a side elevation of a power plow embodying a simple form of the present invention, the two near wheels having been removed to illustrate parts that would be otherwise hidden from view; Fig. 2 is a plan of the plow; Fig. 3 is a view of one end looking in the direction of the arrow 3 in Fig. 2; Fig. 4 is a side view of a bracket and fragment of a plow beam; Fig. 5 is a detail vertical cross section, taken on the line 5—5 of Fig. 2, and showing certain driving mechanism for one of the wheels 45 of the structure; Fig. 6 is a detail end view of the opposite wheel and showing its connection with the frame of the structure and Fig. 7 is a plan of the parts seen in Fig. 6.

Referring to said drawings, 10, designates a main supporting frame, comprising longitudinal members 11, and transverse members 12, secured together to make a strong and substantial frame. Four supporting wheels 13, 14, 15, 16, support said frame and parts carried thereby and three of said

wheels are traction wheels, driven from a motor 17, which motor may comprise an internal combustion engine of any of the well known types used in connection with power driven agricultural implements. The motor 17, is mounted upon cross bars 18, of the main frame 10, and, as shown in the drawings, its driving shaft 19, extends toward the wheels 13, 14, and has secured upon its end a beveled pinion 20, which is arranged to mesh with either of a pair of beveled gear wheels 21, 22, slidably mounted upon a shaft 23, journaled on the frame 10. The beveled gear wheels 21, 22, are connected to the shaft 23 by a spline running in a groove in the shaft, and a lever 24 is provided whereby the beveled gear wheels may be shifted to bring either one into mesh with the beveled pinion 20. This gearing provides one form of means for driving the plow forward or backward, as desired.

Extending parallel with the shaft 23, is a drive shaft 25, journaled on the frame 10, and said shafts 23, 25, are geared together by a pinion 26, fast on the shaft 23, and a gear wheel 27 fast on the shaft 25, and intermeshing with said pinion 26. On the ends of said shaft 25, are sprocket wheels 28, over which are trained sprocket chains 29, which are trained over larger sprocket wheels 30, fast upon the shafts 31, 31^a, of the traction wheels 13, 14. Said shafts 31, 31^a, are journaled in bearing boxes 32, 33, secured to cross bar 12 of the frame. A compensating gear mechanism 34, is interposed in the drive shaft 25, in accordance with the usual practice in the power plant of a motor driven vehicle. The wheels 15, 16, are the steering wheels of the plow and are mounted upon knuckles 35, 36, (see Figs. 4, 5 and 6) the knuckle members 37, 38, having steering arms 39, 40, which are connected together by a connecting rod 41, whereby the steering wheels may be moved in unison. Said connecting rod may be operated by any of the well known forms of steering apparatus and as here shown, is operated from a steering wheel 42, by a worm gear 43, fast on the lower end of the shaft 44, of said steering wheel, and a worm gear 45, fast on a shaft 46, a crank arm 47^a at one end of said shaft 46, that engages with the connecting rod 41.

The traction wheel 15, is driven from the power plant of the machine and one form of driving mechanism is shown to comprise

a sprocket wheel 47, fast on the drive shaft 25, a sprocket chain 48, trained over said sprocket wheel and over a sprocket wheel 49 fast on a shaft 50, journaled in the stationary member of the knuckle 35, as clearly indicated in Fig. 5. The drive wheel 15, is shown as provided with centrally located stem or shaft 51, extending through the member 37 of the knuckle 35, and connected 10 to the shaft 50 by a universal or knuckle joint 52, whereby the wheel 15, may be turned upon the knuckle 35, while being driven by the shafts 50, 51. Obviously any equivalent form of driving mechanism between the drive shaft 25, and the wheel 15, may be substituted for the one shown and described.

The knuckle 36 of the wheel 16, yieldably supports the frame 10, and is shown as slidably mounted in a slide bearing 53, secured to the frame. The member 36^a, of said knuckle rests upon a coil compression spring 54, which is carried by the lower end of the bearing 53, and a coil compression spring 55, rests upon the upper end of the bearing 53, and is connected to the member 36^a of the knuckle by a bolt 56.

The mechanism thus far described comprises a simple form of traction engine and 30 I desire it to be understood that I do not intend to limit myself to the form shown and described as it is obvious that many types of traction engines may be substituted therefor.

35 At each end of the frame of the structure is a plow A, B, each plow being shown as comprising a plow beam 60, and a plow share 61, carried thereby, whose form and construction may comprise any, well known to those skilled in the art, and capable of working in conjunction with the power driven apparatus. The plow shares are in alignment with each other and their points are directed toward each other. The plow beams are shown as pivotally connected to the frame of the machine as at 62, brackets 63^a being secured to the frame of the traction engine and connected to the ends of the plow beams by bolts or otherwise as desired. The plows are located between the pairs of wheels and near the wheels 13, 15, in order that the said wheels 13, 15, may travel in the furrow last made, so that one of the plows will turn up the next furrow at the proper place. Each plow is provided 55 with means for raising or lowering the same, and a simple form of mechanism is shown to comprise a hand lever 63, pivotally mounted upon a standard 64, secured to the frame, and a link 65 connecting one end of the lever 63 with the plow beam 60. If desired a coil tension spring 66, may be interposed between some stationary portion of the frame, for instance the bracket 64 and each plow beam 60, to assist in raising the plow share

out of the furrow. Means are provided for holding the plow in raised position and as shown, a simple means comprises a hook 67, one for each lever 63, under which the handle of the lever 63 may be placed whenever it is swung downward to raise the plow.

In operation one of the plows A, B, for instance the one lettered A, is lifted out of the furrow and held in raised position and the other one (B) is lowered as shown in Fig. 1; the engine having been started, the lever 24 is swung in the proper direction to throw the beveled gear wheel 21 into mesh with the beveled pinion 20, thereby causing the power plant to drive the structure in the direction of the arrow *a*, in Fig. 1. When arriving at the end of the field, the machine is steered out of its course so as to bring the wheels 13, 15, into alignment with the furrow just made; the plow B, is then raised out of the furrow and the plow A, lowered. The apparatus is then driven forward with the wheels 13, 15, running in the furrow just made, and the plow A, thereupon cuts the next furrow at the proper distance away from the first one. In this way the machine can be driven forth and back across the field without the necessity of turning it around. Obviously gangs of plows may be substituted for the single plow, without departing from the spirit of this invention.

A particular advantage is obtained by reason of the fact that the two wheels, 13, 15, are so arranged with respect to the plow shares that they travel in the previously made furrow because the ground in the furrow is usually firm and even so that the two wheels, 13, 15, obtain better traction than the one, 14, on the land side. The efficiency of the machine is thereby greatly increased without the necessity of an abnormally high powered engine.

More or less alterations and modifications are possible without departing from the spirit of this invention and I desire, therefore, not to limit myself to the exact form and construction shown and described, but intend in the following claims to point out all of the invention disclosed herein.

I claim as new and desire to secure by Letters Patent:—

1. In a power plow, a motor driven, wheeled structure having two rear drive wheels and a front driven wheel in line with one of the rear drive wheels, plows and raising mechanism therefor at the ends of said structure, said plows pointed toward each other and trailing adjacent the front driven wheel and rear drive wheel in line therewith, said plows being disposed relative to said aligned front and rear drive wheels in such manner that said aligned wheels may travel in a furrow and the plow cut the next furrow.

2. In a power plow, a motor driven,

wheeled structure having two rear drive wheels and a front drive wheel in alinement with one of said rear drive wheels, alined plows, one secured to said structure at each 5 end thereof and pointed toward the other, operating means for raising and lowering said plows and means for holding said plows in raised position, said plows being disposed relative to said alined drive wheels in such 10 manner that said alined drive wheels may travel in a furrow and one plow cut a next adjacent furrow.

3. In a power plow, a four wheeled structure, a motor carried by said structure and 15 drive mechanism between said motor and

three of the wheels of said wheeled structure and including reversing mechanism for reversing the direction of travel of the plow, two of said drive wheels being in alinement with each other, oppositely pointing, alined 20 plows secured to the ends of said structure, and plow raising and lowering mechanism, said plows being disposed relative to said alined drive wheels in such manner that said alined wheels may travel in a furrow and 25 the plow cut a next adjacent furrow.

WILLIAM W. GREEN.
